UNITED STATES PATENT OFFICE.

ARTHUR ERNEST JERRAM, JOSEPH GOULBOURN, AND ARTHUR BATES, OF LEICESTER, ENGLAND, ASSIGNORS TO UNITED SHOE MACHINERY COMPANY, OF PATERSON, NEW JERSEY, A CORPORATION OF NEW JERSEY.

HEELING-MACHINE.

1,157,689.

Specification of Letters Patent.

Patented Oct. 26, 1915.

Application filed September 9, 1910. Serial No. 581,171.

To all whom it may concern:

Be it known that we, ARTHUR E. JERRAM, JOSEPH GOULBOURN, and ARTHUR BATES, subjects of the King of England, residing at 5 Leicester, Leicestershire, England, have invented certain Improvements in Heeling-Machines, of which the following description, in connection with the accompanying drawings, is a specification, like reference 10 characters on the drawings indicating like parts in the several figures.

This invention relates to heel nailing machines, including those used for loading heels with nails or other fasteners and those 15 for attaching heels to boots or shoes. As regards its application to machines of the latter type, it may be equally well embodied in those in which the nails are driven from inside the shoe as in those in which the 20 nails are driven from the outside, through the heel into the heel seat of the sole.

The object of the invention is to improve the general construction and organization 25 of such machines whereby they may be operated with greater certainty, precision and convenience than machines heretofore constructed.

In heel nailing machines there are provided two work-engaging members arranged 30 to hold the work under pressure during the nail driving operation. It is important that each heel operated upon should be subjected to a uniform degree of pressure regardless 35 of differences in height and it is desirable that such uniform action be obtained without the necessity of a separate adjustment in each case. To this end an important feature of the invention consists in the provision 40 of relatively movable work-engaging members which may be brought into contact with the opposite sides of the work to measure or preliminarily engage the work, and power operated mechanism arranged to actuate said work-engaging members with a 45 predetermined pressure regardless of the thickness of the work held between them. As herein shown, and in accordance with another feature of the invention, mechanism is further provided for locking the work- 50 engaging members under such predetermined pressure during the nailing operation. Preferably the construction is such that

work-engaging members are automatically unlocked at the conclusion of the driving operation.

In a preferred construction, the work-engaging members may be moved relatively to engage the work by the preliminary movement of a manually operated controlling device and, by a further movement of the same 60 device, automatic mechanism may be thrown into operation first to exert pressure on the work, then to lock the work-engaging members against relative movement, and finally to unlock said members to permit the removal of the work.

Another feature of the present invention consists in arranging the actuating mechanism of the nail drivers to impart to the drivers a plurality of nail driving strokes 70 while the work is held under pressure. In heel nailing machines as heretofore constructed the drivers have made only one driving stroke to insert the nails in the work. By imparting to the drivers two or more 75 strokes, however, as contemplated by the present invention, improved results are obtained and the nails are driven with greater precision than heretofore. One manner of effecting the desired result consists in providing a toggle having one end connected 80 to the drivers and the other end normally free but constructed and arranged to be held stationary when it is desired to effect the actuation of the drivers. An operative connection may be arranged between the toggle and the driven shaft of the machine to break 85 the toggle first on one side and then on the other thereby actuating the drivers each time the toggle is straightened.

In a preferred embodiment of the invention the means for locking the end of the toggle to effect the actuation of the drivers is controlled by the manually operated device, above referred to, for relatively moving the work-engaging members into contact with the work, said device also controlling the action of the power-operated mechanism for applying pressure to the work and for locking the work under pressure. In a construction wherein said power-operated mechanism is employed to actuate the locking means for the pressure applying members, there may be provided yielding or other lost

motion connection between the mechanism and the locking means to permit the application of the full predetermined pressure before the action of the locking means takes place.

For purposes of illustration we have shown the invention as embodied in a machine wherein the predetermined pressure is imparted to the work-engaging members by hydraulic means, but this construction is illustrative only and it is within the scope of the invention to substitute mechanical means if preferred.

These and other features of the invention will be best understood and appreciated from the following description of one example thereof as embodied in a heel attaching machine.

In the accompanying drawings, Figure 1 is a side elevation of a heel attaching machine embodying the present invention; Fig. 2 is a front elevation of the machine shown in Fig. 1; Fig. 3 is a view, partly in section, showing in detail the rotary valve and its associated mechanism; Fig. 4 is a view, partly in section, of the pump and the adjacent parts of the machine; Fig. 5 is an enlarged sectional view of the pump; Fig. 6 is an enlarged sectional view of the lower part of the machine shown in Fig. 1; Fig. 7 is a similar view of the upper part of the machine; Fig. 8 is a plan view of the band clamp and its mounting.

In the machine shown in the drawings there are two work-engaging members 2 and 4 arranged for relative vertical movement for clamping the work. The lower member 4 is constructed so as to permit nails to be driven from it into the work by drivers which are arranged to operate within said lower member and are carried by a plunger 6. The upper member 2 is constructed and arranged to be moved into various positions according to the height of the heel being attached and according to the degree of compression to be exerted upon the heel.

In the machine herein illustrated the upper work-engaging member 2 is attached to the lower end of a plunger 8 mounted for vertical sliding movement in bearings in the head 10 of the machine. The plunger 8 is provided with a recess 12 in which engages one end of a lever 14 fulcrumed on a pivot 16 to the frame of the machine. The other end of the lever 14 is connected with the piston or plunger 18 of the cylinder 20 by a link 22, one end of which is connected to the lever 14 by a pin 24 and the other end is connected to the plunger 18 by a pin 26. Mounted yieldingly, as hereinafter described, upon the pivot 16 on which the lever 14 turns is another lever 28 terminating at its forward end in a handle 30 and connected at its rear end to the pin 24.

The lever 28 is yieldingly mounted upon

its pivot 16 by the provision of a slot 32 in the lever through which slot the pivot 16 passes, a spring pressed plunger 34 located in a recess in said lever acting to maintain normally the lower end of the slot 32 in contact with the pivot 16, as shown in Fig. 7. When the handle 30 is depressed, the two levers 14 and 28 will move simultaneously until the downward movement of the plunger 8 is prevented by the engagement of the presser member 2 with the work upon the support 4. When the work is thus clamped the hand operated lever 28 is further depressed in opposition to the plunger 34 to throw into action mechanism for admitting fluid under pressure beneath the piston or plunger 18 to exert pressure upon the work through the lever 14 and also to actuate the nail-driving mechanism as will be hereinafter explained.

The fluid, preferably oil, may be supplied to the cylinder 20 from an accumulator 36 located at the rear of the machine or in any other convenient situation. The fluid is conducted through passages 38, see Fig. 4, from the accumulator 36 to a rotary valve 40 which may be frusto-conical in form as shown in Fig. 3 and preferably balanced. The valve 40 connects with a passage 42 which in one position of the valve establishes connection between the accumulator 36 and the cylinder 20 by way of the passage 38. In another position the rotary valve closes the passage 38 leading to the cylinder whereby the fluid is locked therein and the work maintained under pressure. In a third position, corresponding to that shown in full lines in Fig. 4, the valve 40 puts the passage 42 in communication with a reservoir 44 through the passage 46 so as to permit the fluid contained in the cylinder 20 to pass therefrom freely to the reservoir, or vice versa, thus permitting unrestrained movement of the plunger 18.

The rotary valve 40 has secured upon its spindle 48 an arm 50 which is connected by a rod 51 to a lever 52 operated by a cam 54 upon the main shaft 56 of the machine, the lever 52 being fulcrumed at 53 upon a sliding clutch bolt 58 shown in Fig. 6. The clutch bolt 58 at times can be held stationary by mechanism controlled by the hand operated lever 28 so that the cam 54 can thereby effect the changes in position of the rotary valve. At other times the clutch bolt 58 will be free to move permitting the cam 54 to oscillate the lever 52 idly about its forward end without moving the valve. This mechanism will be more particularly described hereinafter.

The machine is provided with a pump 60, best shown in Fig. 4, which maintains the fluid in the accumulator 36 and the passages leading to the cylinder 20 under substantially uniform pressure. The pump 130

comprises a cylinder 64 in which a piston 63 carried by a piston rod 65 reciprocates. The piston is attached to the rod 65 by a member 66 which is rigidly attached to the piston rod 65 and slides to a limited extent, as will presently appear, in the interior of the piston 63. This sliding motion of the member 66 relatively to the piston is obtained by a lost motion connection which comprises a pin 68 passing through the piston and engaging in a slot in the member 66. The flange 67 is formed near the upper end of the piston rod, being formed as a valve to engage a seat at the lower part of the piston 63. It will thus be seen that on the down-stroke of the piston 63 a space will be left between the flange and its seat so that fluid can thus freely pass through the piston. On the up-stroke of the piston the flange 67 will be forced against its seat so that the oil which has passed into the interior of the piston on the down-stroke will be forced upwardly past the ball check valve 62 which is provided at the upper end of the cylinder. A spring-pressed ball valve 69, comprising the intake valve, closes the passage 39 communicating with the cylinder 64 and the passage 46. The cylinder 64 passes through the passage 46, an annular passage being provided around the outside of said cylinder so that the oil can pass between the cylinder and the reservoir.

The mechanism for controlling the clutch bolt 58 through which the valve 40 is operated and by which the driver mechanism is controlled will now be described. The pin 24 connecting the ends of the two levers 14, 28 with the link 22 has pivoted thereto a second link 70 which operates a lever 71 pivoted to the frame of the machine at the rear of the work support 4. The lever 71 is provided with a pin 72 arranged to engage a block 73 slidably mounted upon a rod 74 pivoted at its upper end to a lug on the hand lever 28 at a point below and adjacent to its yielding connection with the pivot 16. During the initial movement of the hand lever 28, while it is swinging about the center pivot 16 as an axis, no appreciable longitudinal movement is imparted to the rod 74, and it is only when the hand lever swings about its rear end, after the work has been preliminarily engaged, that effective longitudinal movement is imparted to the rod 74. The lower end of the rod 74 is provided with a plunger 75, see Fig. 6, arranged for sliding movement within a bearing in a projecting boss 77 on the frame of the machine. Pivotally mounted in ears on the plunger 75 is a finger 78 having a projection 79 which is at times adapted to be engaged by the extremity of a rod 80 threaded at its upper end into the block 73. A separate bearing 81 in the boss 77 is provided for the lower end of the rod 80. The pivoted finger 78 on

the plunger 75 may be yieldingly maintained in its different positions by providing flat portions 82 on its upper end co-operating with a small spring-pressed pin 83 located in a recess in the plunger 75.

The clutch bolt 58, hereinbefore referred to as carrying the cam-operated lever 52 and as being capable either of idle movement as the cam is rotated or of remaining stationary, is arranged for sliding movement in bearings 85 in part of the machine frame and is provided with a notch or recess 86. A detent 88 pivoted to the frame at 89 is adapted to engage the notch 86 during a portion of the cycle so as to hold the clutch bolt from movement. The detent 88 is provided with a tail 90 carrying a spring-trip pawl 92 which engages a projection 94 on the frame of the machine and normally maintains the detent in its inoperative position, that is, out of engagement with the notch 86 of the clutch bolt.

The finger 78 on the plunger 75 is adapted, when the hand lever 28 is depressed in opposition to the spring pressed plunger 34 and turns about its rear end as an axis, to engage the spring-trip pawl 92 and release the same from the projection 94 on the frame. This permits the detent 88 to be swung about its pivot 89 by a tension spring 96 and thereby causes the end of the detent to engage in the notch 86 in the clutch bolt 58 and thus lock the latter in position. This will therefore cause the center 53 of the cam-operated lever 52 to be held stationary while the cam 54 will operate to oscillate the lever 52 first to open connection between the accumulator 36 and the cylinder 20, then lock the cylinder while under pressure and finally open the discharge passage of the cylinder to the reservoir 44.

The upper end or tail 90 of the detent 88 when moved by its spring 96 engages the finger 78 on the plunger 75 and turns said finger into a position clear of the spring-trip pawl 92. The finger 78 can only be returned to its operative position by raising the hand-operated lever 28 to the top of its stroke, the return of the finger 78 being effected by the end of the rod 80 which is connected with the block 73. The block 73 is operated by the pin 72 on the lever 71, the lever 71 being operated by the rod 70. This has the effect of insuring that only one complete cycle of operations can take place before a further tripping of the operating mechanism by the finger 78.

A stud 100 on the face of the cam disk 54 is arranged to contact with a tappet piece 101 pivotally attached to the detent 88, in order to move said detent out of engagement with the clutch bolt 58 at the time required in the cycle of the machine. The tappet piece 101 is pivotally connected by a pin 102 to the detent and is held yieldingly

in position by a spring 103 so that when engaged by the stud 100 it may be rocked slightly in effecting the displacement of the detent 88 sufficiently to clear itself from the path of the stud. When the detent is displaced the spring 96 is placed under tension and the detent is latched in its initial position by the trip pawl 92 and the stop 94.

The nail-driving mechanism which, as hereinbefore indicated, is also controlled by the hand-operated lever 28, is so constructed and arranged as to deliver two blows on the attaching nails during each cycle of the machine. The nail drivers are carried on the plunger 6 which is connected at its lower end to one link 105 of a toggle, the end of the other link 106 of the toggle being connected to a second plunger 108 mounted in bearings 110 in the lower part of the frame of the machine. The second plunger 108 is normally free to reciprocate in its bearings so that the plunger 106 carrying the nail drivers will remain inoperative, the toggle straightening and breaking idly.

At times, however, the second plunger 108 may be held stationary, as hereinafter explained, so that the toggle will become operative to lift the plunger 6 and the nail drivers. The joint 112 of the toggle is connected by a connecting rod or pitman 114 with a crank pin 116 on the main shaft 56 and the toggle and the crank are so arranged that, when the lower plunger 108 is fixed, one revolution of the shaft will move the toggle from its broken position into a straightened position and then break it on the other side to a limited degree, afterward straightening the toggle again and finally returning it to its original position, thereby securing a double reciprocation of the plunger 6 and the drivers for one revolution of the main shaft. The preferred construction for holding the lower plunger 108 stationary consists in providing a horizontally sliding bolt 118 which may be moved under the lower end of the plunger to lock it in its raised position. To operate the sliding bolt there is provided a lever 119 pivoted at 120 upon the frame, said lever being connected at its upper end by a link 121 to the cam-operated lever 52. The lever 119 is so arranged that it will operate the sliding bolt 118 whether or not the plunger 108 is raised synchronously with its forward movement. To this end there is mounted on the lower end of the lever an arm 122 on either side of which are jaws 123 normally drawn together against a pin 124 projecting from the end of the arm by a spring 126. The ends of the jaws 123 project beyond the end of the arm 122 and extend, one on each side of the pin 125 on the sliding bolt. By this construction, when the lever 119 is turned upon its center, one of the jaws will press against the pin 125

thereby imparting a pressure to the bolt 118 which will be effective to slide the latter forwardly and beneath the end of the plunger when the plunger is raised.

The bottom of the plunger 108 is provided with a recess 128 into which fits a corresponding projection 130 on the sliding bolt 118, the projection and the recess being sufficient to hold the bolt in engagement with the plunger until the toggle is broken to its utmost extent. As indicated in Fig. 1 the toggle is not broken forwardly to an extent sufficient to lift the lower plunger 108. At that time the plunger 6 contacts with a stop, not shown, limiting its downward movement so that the plunger 108 will be raised sufficiently to disengage the bolt.

In the operation of the machine hereinbefore described, the shoe and heel are placed between the members 2 and 4 and, by means of the handle 30, the operator lowers the upper member 2 to measure and clamp the work against the lower member 4. A further depression of the handle 30 forces the rod 74 downwardly and the finger 78 trips the spring-trip pawl 92 on the detent 88 thus allowing the spring 96 to force the detent into engagement with the notch 86 in the clutch bolt 58, this being permitted by the cam on the main shaft.

The clutch bolt 58 will now be locked against movement and the cam-actuated lever 52 will be oscillated by its cam 54 to depress the rod 51 and open the valve 40 allowing the fluid under pressure to flow into the cylinder 20 and raise the piston 18. This will cause the member 2 to descend and exert a predetermined preliminary pressure upon the work regardless of its thickness or density. The cam 54 will then move the valve 40, through the connections hereinbefore described, so that the fluid will be retained in the cylinder, thereby locking the two clamping members in their work-compressing position. Finally the valve will be turned so as to allow the fluid to escape from the cylinder and the clamping members may be thereupon moved apart to release the work.

During this operation of the lever 52 the sliding bolt 118 is operated to lock the lower plunger 108 against movement so that the toggle 105, 106 will no longer work idly but will operate the drivers, as already explained, twice in one revolution of the main shaft while the members 2 and 4 are locked under pressure.

After the nail-driving operation has been effected and the pressure of the clamping members upon the work has been removed, the sliding bolt 118 is withdrawn to permit the toggle to again move idly. While the toggle is moving idly, the detent 88 is withdrawn from the notch 86 in the clutch bolt leaving the machine in readiness for the in-

sertion of new work. As already pointed out the movement of the detent 88 into position to secure the clutch bolt from movement has the effect of tipping the finger 78 5 out of operative relation to the spring-trip pawl 92 on the detent 88. The finger 78 will remain in this inoperative position until the hand operated lever 28 has been raised to its fullest extent when the rod 80 will 10 engage the projection 79 on the finger and thus return it to its operative position ready for the next cycle.

The machine hereinabove described is adapted either for driving the attaching 15 nails from the inside of the shoe into the heel or through the heel into the heel seat of the sole. The work supporting members shown in Fig. 1 are adapted to hold the work for inside nailing and those shown in Fig. 20 7 are adapted to hold the work for outside nailing.

The clamping device which is intended especially for outside nailing comprises a band clamp 132 adapted to surround partially the rear part of the boot. As shown 25 in Fig. 8, the band clamp is supported on either side by tubular links 133 connected by pivots 135 to the forward ends of levers 134 pivoted at 138 on a slide member 140. The links 133 are preferably made adjustable by means of screws 142 bearing on 30 rods 144 slidably mounted in the bore of the links and pivoted at their inner ends to the band clamp. The levers 134 are adjustable simultaneously by means of a screw 35 148 having a right and left thread. By this means the spread of the band clamp may be varied. The slide 140 to which the levers 124 are pivoted is adjustable toward and 40 from the work in a guideway 150, a rack 151 and pinion 152 being employed for purposes of adjustment. The guideway 150 is formed in a block provided with a stem 154 mounted for vertical and angular adjustment 45 in an arm 160 depending from the plunger 8, the stem 154 being secured in its adjusted position in the arm by a clamping screw 155.

The jack 162 for carrying the work is also 50 made adjustable independently of the band clamp. To this end it is mounted on a slide 163 transversely movable in a substantially horizontal guideway formed in the boss 164 of the arm 160. An adjusting screw 165 may be provided for moving the slide 163.

In order that the band clamp may be 55 readily interchangeable to fit shoes of various sizes, it is provided with a stem 169 received in the bore of a screw 166 adjustable inwardly and outwardly in the slide member 140. The screw 166 is threaded into a recess in said slide and may be adjusted by means of a milled nut 168 which is held 60 against movement longitudinally of the screw. The mechanism above described is

not herein claimed as it forms the subject-matter of our divisional application Serial No. 9,393, filed February 19, 1915.

Having now described my invention, what I claim as new and desire to secure by Letters Patent of the United States is:—

1. A machine of the class described having, in combination, means for holding a heel under pressure, a gang of drivers and actuating means therefor constructed and arranged to impart to the gang of drivers a plurality of driving strokes terminating at the same point while the heel is held continuously under pressure and then automatically to bring the drivers to rest. 75

2. A machine of the class described having, in combination, means for holding a heel under pressure, nail drivers, actuating means therefor including a toggle constructed and arranged to be broken alternately 80 on either side of its straightened position whereby two driving strokes may be imparted to the drivers while the heel is held continuously under pressure and mechanism for automatically rendering the toggle 85 inoperative after it has twice operated the drivers. 90

3. A machine of the class described having, in combination, means for pressing a heel against a shoe, nail drivers, and actuating means therefor including a toggle having a floating end, and movable means for anchoring said end to render the toggle effective. 95

4. A machine of the class described having, in combination, means for pressing a heel against the heel seat of a shoe, nail drivers, and actuating means therefor including a toggle, movable plungers connected therewith, and movable means for holding one plunger stationary to render the toggle effective. 100 105

5. A machine of the class described having, in combination, relatively movable heel pressing members, nail drivers and actuating mechanism for the drivers including a toggle normally inoperative to move the drivers, and a sliding bolt movable to render said toggle effective. 110

6. A machine of the class described having, in combination, work holding means, nail drivers and actuating mechanism therefor including normally inoperative means for reciprocating the drivers, a sliding bolt, and means for imparting a continuous impulse to said bolt tending to move it to render said normally inoperative means effective. 115 120

7. A machine of the class described having, in combination, work holding means, nail drivers and actuating means therefor including normally inoperative means for reciprocating said drivers, a sliding bolt and a lever having a yielding portion for imparting a continuing impulse to said bolt 125 130

- 6 tending to move it to render said normally inoperative means effective.
8. A machine of the class described having, in combination, work holding means, 5 nail drivers, and actuating means therefor including a toggle normally arranged for idle operation, and cam operated means for rendering said toggle effective.
9. A machine of the class described having, in combination, work holding means, 10 nail drivers, and actuating means therefor including a toggle normally arranged for idle operation; cam operated means for rendering said toggle effective, and a manual controlling device for said cam operated means.
10. A machine of the class described, having, in combination, movable work holding means, nail drivers and actuating means 15 therefor including a toggle normally arranged for idle operation, a sliding abutment movable into and out of the path of one end of said toggle to render it effective, a pivoted lever for moving said abutment, 20 cam operated means for moving said lever and a manually operated device for controlling movement of the work holding means and said latter cam operated means.
11. A machine of the class described having, in combination, means for holding the work under pressure, nail drivers, actuating means therefor including a member mounted for idle reciprocation, and a movable device 25 for engaging said member to render the driver actuating means effective, said device being constructed and arranged to be locked in engaging position.
12. A machine of the class described having, in combination, work supporting means, 30 nail drivers, a toggle for actuating said drivers, a reciprocatory plunger connected with said toggle and a sliding bolt arranged for locking engagement therewith.
13. A machine of the class described having, in combination, nailing mechanism, a 35 stationary work-engaging member and a relatively movable work pressing member, means for moving said pressing member into engagement with the work, and power 40 actuated means for effecting a further movement of said pressing member arranged to exert a uniform pressure regardless of the thickness of the work.
14. A machine of the class described having, in combination, nailing mechanism, a 45 stationary work-engaging member and a relatively movable work pressing member, means for moving said pressing member into engagement with the work, and power 50 actuated means constructed and arranged to press said member upon the work with a predetermined pressure regardless of the thickness of the work.
15. A heel attaching machine having, in 55 combination, a nail block, a shoe support arranged for movement from and toward the block, means for moving the shoe support toward the nail block to bring a shoe and heel into preliminary engagement constructed to limit the pressure of such engagement, 60 and means for automatically moving the shoe support toward the nail block to subject the shoe and heel to a uniform pressure prior to the attaching operation.
16. A heel nailing machine having, in combination, 75 a nail block, a shoe support arranged for movement toward the nail block to bring a heel and shoe into preliminary engagement, means for automatically moving the shoe support toward the nail block to 80 subject the shoe and heel to further pressure, and a single device for controlling the preliminary movement of the shoe support and its automatic actuation.
17. A heel nailing machine having, in combination, work pressing members, power operated mechanism for relatively moving said members to exert a predetermined pressure upon the work located between them regardless of its thickness, and a device to lock 90 said members in such position of pressure.
18. A machine of the class described having, in combination, work pressing members, power operated means for moving said members toward each other with a uniform pressure and to a final relative position determined by the density of the work located between them, and nail driving mechanism 95 arranged for automatic operation while the work is so held.
19. A machine of the class described having, in combination, a nail block, a jack, power operated means for moving said jack toward the nail block with a uniform pressure and to a final position determined by 105 the density of, or the resistance offered by, the work located on the nail block, and driving mechanism arranged for automatic operation while the work is held under uniform pressure.
20. A machine of the class described having, in combination, relatively movable pressing members, means for subjecting the same to fluid pressure, a controlling valve, drivers, and a hand operated lever for moving 115 said pressing members into engagement with the work, said lever, by a further movement, effecting automatically the operation of the controlling valve whereby the pressing members are first subjected to fluid pressure, then locked under pressure and finally released, said lever meantime also controlling the operation of the drivers.
21. A machine of the class described having, in combination, a nail block and pressing member, means for moving them together to subject heels of varying heights 120 placed between them to uniform pressure,

- said means including a pump acting by fluid pressure on said pressing member, and drivers working in said nail block.
22. A machine of the class described having, in combination, relatively movable pressing members, a pivoted lever for transmitting pressure to one of said members, a controlling lever movable simultaneously with said first mentioned lever, cam controlled means for regulating the application of pressure to said pivoted lever and connections between said controlling lever and said cam controlled means for rendering the latter effective.
23. A machine of the class described having, in combination, relatively movable pressing members, power actuating means therefor, a device for regulating the application and removal of pressure by said actuating means, a cam operated lever having a floating pivot and being connected with said regulating device, and a hand lever for moving said pressing member into engagement with the work and also anchoring the pivot of said cam operated lever in order to effect actuation of said regulating device.
24. A machine of the class described having, in combination, a nail block and pressing member, means for moving them together to subject heels of varying heights placed between them to uniform pressure preliminarily to the nailing operation, said means including a fluid pressure system and an automatic controlling valve therein, and nail drivers arranged to reciprocate in said nail block.
25. A machine for operating on heels having, in combination, means for holding a heel, a gang of tools arranged to operate upon a heel so held, and means for imparting to said gang of tools two working strokes to perform a single operation on the heel, each stroke terminating at the same point but having a different starting point.
26. A machine for operating upon heels having, in combination, means for applying pressure to the work, a movable controlling device for said means, and power operated means for moving the controlling device including a member having normally an idle movement, a lock for said member, a spring for the lock arranged to be latched under tension at the conclusion of each cycle, and a starting lever by which the lock may be tripped.
27. A machine of the class described having, in combination, nail driving mechanism, a nail block, a pressing member movable relatively thereto, a lever pivoted between its ends and connected at one end to said pressing member, a manually operated lever arranged to act upon the opposite end of said first mentioned lever to move said pressing member into engagement with work presented upon the nail block, and means for actuating said driving mechanism arranged to be set in motion by a further movement of said manually operated lever.
28. A machine of the class described having, in combination, a nail block, a work pressing member movable relatively thereto, a manually operated lever for moving said pressing member toward or away from said nail block, rods connected with said lever at separate points, and power actuating means for said pressing member, one of said rods operating to set in motion said power actuating means when the lever is moved in one direction and the other of said rods acting, when the lever is moved in a reverse direction, to render the subsequent movement of the first mentioned rod effective.
29. A machine for operating upon heels having, in combination, means for applying pressure to the work, a movable device for controlling the application and removal of pressure by said means, and power operated means for moving the controlling device, including a cam lever having normally an idle oscillation, a locking detent for the lever arranged to be placed under spring tension by the power of the machine, and a starting lever by which the locking detent may be tripped and so rendered operative.
30. A machine for operating on heels having, in combination, relatively movable heel pressing members, means for preliminarily moving one toward the other to measure the work, fluid pressure means for further moving one toward the other to apply a predetermined pressure to the work, means for locking the members so moved rigidly in its position of pressure, and a gang of tools arranged to operate upon the work while held under pressure.
31. A machine for operating on heels having, in combination, relatively movable heel pressing members, means for preliminarily moving one toward the other, to measure the work, a fluid pressure cylinder having a piston connected to one of said members and arranged to be subjected to a predetermined amount of fluid pressure, and means for automatically closing the cylinder to lock the pressing member under pressure.
32. A machine for operating on heels having, in combination, a gang of tools, power actuating mechanism for the tools, coöperating work-engaging members, one being movable relatively to the other to effect the measuring operation, a manually operated device including a movable clutch tripping piece, said device being arranged in its initial movement to control the measuring movement of a work-engaging member and in its final movement to start the power ac-

tuating mechanism through the tripping piece, and means for moving said piece into an inoperative position to insure non-repeating operation of the machine.

5 33. A machine for operating on heels having, in combination, a gang of tools, coöperating work-engaging members of which one is power operated, a manually operated device for controlling the measuring move-
10 ment of a work-engaging member, said device being arranged to initiate the power operation of the work-engaging member, and means for rendering said device inop-
erative for this purpose after said operation
15 has been initiated.

34. A machine for operating on heels having, in combination, a gang of power operated tools, coöoperating work-engaging members, manually operated means for controlling the preliminary measuring movement of a work-engaging member, said means being arranged to control the starting of the power operated tools and mechanism for rendering said manually operated means inoperative for this purpose after the tools have been started.

35. A machine of the class described having, in combination, a gang of tools, a die block, a pressing member movable relatively thereto, a pressing lever mounted to turn about an intermediate axis and connected at one end to said pressing member, a manually operated lever arranged to turn about the same axis to move the pressing lever so as to bring the pressing member into engagement with work between it and the die block, and means for actuating the driving mechanism arranged to be set in motion by a further movement of said manually operated lever.

36. A machine for operating upon heels, having, in combination, oppositely arranged pressing members, tools for operating on a heel held by said members, a device constructed and arranged to be moved by the power of the machine during each cycle and to be latched under spring tension when the machine comes to rest, a train of mechanism actuated when said device is moved from its latched position and constructed and arranged to control the movement of one of the pressing members for applying a measuring pressure to the work, a lever manually operable for tripping said device and also setting the tools of the machine in operation, and means for moving said pressing member farther in the same direction to increase the pressure on the work. 45 50 55

37. A machine for operating on heels, having, in combination, relatively movable heel pressing members, means for preliminarily moving one toward the other to measure the work, fluid pressure means for moving one toward the other to apply a predetermined pressure to the work, an accumulator for supplying fluid, means for locking that member which has been moved rigidly in its position of pressure, and a gang of tools arranged to operate upon the work while held under pressure. 70 60 65 70

In testimony whereof we have signed our names to this specification in the presence of two subscribing witnesses.
